UNITED STATES PATENT OFFICE.

EMIL ARTHUR SCHUELKE, OF MERIDEN, CONNECTICUT, ASSIGNOR TO THE NAPIER CO.,
OF MERIDEN, CONNECTICUT, A CORPORATION OF CONNECTICUT.

DESIGN FOR A NECKLACE OR SIMILAR ARTICLE.

Application filed February 9, 1928. Serial No 25,308. Term of patent 7 years.

To all whom it may concern:

Be it known that I, EMIL A. SCHUELKE, a citizen of the United States, residing at Meriden, in the county of New Haven and State of Connecticut, have invented a new, original, and ornamental Design for Necklace or Similar Article, of which the following is a specification, reference being had to the accompanying drawing, forming a part thereof:

Figure 1 is a plan view of a necklace showing my new design, and

Figure 2 is a rear perspective view of a portion thereof.

I claim:

The ornamental design for a necklace or similar article as shown.

EMIL ARTHUR SCHUELKE.
